UNITED STATES PATENT OFFICE.

PERCY W. HATFIELD, OF WAKEFIELD, MASSACHUSETTS, ASSIGNOR TO WINSHIP, BOIT & CO., OF WAKEFIELD, MASSACHUSETTS, A COPARTNERSHIP CONSISTING OF CHARLES N. WINSHIP AND ELIZABETH S. BOIT.

LABEL-SEWING MACHINE.

Application filed April 17, 1922. Serial No. 553,433.

This invention relates to sewing machines, and is especially concerned with sewing machines of the character designed to sew labels on to undergarments or other work. 5 The type of machine usually employed for this purpose at the present time includes a single needle guided in a hollow rectangular presser foot so that it sews around all four edges of the label. The present invention 10 aims to devise a mechanism with which the labels can be secured to the work more neatly and expeditiously. The invention contemplates a machine which will secure a label or similar article to the work by sewing simultaneously across its opposite edges, and combines with such a mechanism means for properly presenting the label to the needles. It preferably includes also mechanism 15 for turning under the edges or ends of the label prior to being sewed by the needles and means for automatically stopping the machine when the sewing operation has been completed.

The nature of the invention will be readily understood from the following description when read in connection with the accompanying drawings, and the novel features will be particularly pointed out in the appended claims.

30 In the drawings,

Figure 1 is a view, partly in side elevation and partly in cross section, of a sewing machine modified in accordance with the present invention;

35 Fig. 2 is a plan view showing the manner in which this machine secures a label to the work;

Fig. 3 is a cross sectional view through one of the seams which secures the label to the work;

40 Fig. 4 is a cross sectional view through a portion of the mechanism that controls the feeding of the work;

Fig. 5 is a plan view of the plunger used in the mechanism shown in Fig. 4;

45 Fig. 6 is a plan view of the mechanism for starting and stopping the machine and controlling the feeding of the work;

Fig. 7 is an end view of the mechanism 50 shown in Fig. 6;

Fig. 8 is a side elevation of the label handling mechanism provided by this invention;

Fig. 9 is a front elevation of the mechanism shown in Fig. 8;

Fig. 10 is a cross sectional plan view on the line 10—10, Fig. 8;

Fig. 11 is a cross sectional view on the line 11—11, Fig. 9; and

Figs. 12, 13 and 14 are views, partly in cross section and partly in front elevation, showing successive steps in the process of folding the ends of the label. The plane of cross-section of these views is substantially as indicated by the line 12—12, Fig. 8.

Referring first to Fig. 2, L designates a label bearing the maker's trade-mark, or other subject matter, and secured to a portion of the garment or other piece of work W by seams or lines of stitches S—S. This figure indicates the nature of the work which the present machine is intended to perform.

The mechanism embodying the present invention is shown in the drawings as applied to a Singer sewing machine, designated in general at 2, and provided with a needle bar 3 carrying a needle holder 4 in which are mounted two needles 5—5. The machine also includes a presser foot 6 mounted on the lower end of a presser foot bar 7. All these parts are constructed, arranged and operated in the usual manner.

The label holding mechanism shown comprises a plate or holder 10, of approximately the length of a label, secured to the lower part 12 of a U-shaped frame having two side members 14 and 15. The plate 10 forms, in effect, a continuation of another plate 16 having its sides turned upwardly, as clearly shown in the drawings, to form a chute or hopper. The upper ends of the arms 14 and 15 are slotted to receive screws 18 and 19, respectively, by means of which they are secured to the opposite sides of a bracket 20 which is fastened to the presser bar sleeve 21 by a set screw 22. The arms 14 and 15 are pivoted on the opposite ends of a yoke 23 which is secured to the presser foot bar 7 by means of a set screw 24, screws 26 and 27, respectively, holding the two arms on the ends of the yoke. It will now be evident that when the presser foot bar is raised to lift the presser foot 6, the connections between this bar and the label holder will 105 swing the label holder upward and forward.

into approximately the relationship shown in Fig. 11.

In order to assist the operator in properly positioning a label in the holder, two stops 30-30 are positioned near the forward edge of the holder. Each stop consists of a wire having a right angle bend therein, as clearly shown in the drawings, and both stops are secured in a small rock shaft 31 mounted in ears that project from the lower sides of members 32 and 33, respectively, which are secured to the opposite ends of a bar 34 guided in slots in the members 14 and 15. The parts 32 and 33 are secured on the lower ends of rods 36 and 37, respectively, carrying studs 38 and 39 at their upper ends which project through cam slots formed in disks 40 and 41, respectively, the cam groove in the part 40 being shown at 42, Fig. 8, and that in the other cam being identical with it.

These cam disks 40 and 41 are mounted to rotate on the opposite ends of the yoke 23 and they are connected together by a bar 43 so that they are compelled to rotate in unison. A pin 44, Fig. 9, projecting inwardly from the cam 40 enters a slot formed in the lower part of a bracket 45 which is secured to the machine frame. Consequently, when the presser foot bar is raised and lowered these connections produce a rotating movement of the cams 40 and 41, which movement is transmitted to the members 32, 33 and 34, reciprocating these members in a direction parallel to the side pieces 14 and 15 of the label holder frame. The rock shaft 31, on which the stops 30-30 are mounted, carries a forked piece 47 which straddles a pin 48 secured in the bar 15. The paths in the cams 40 and 41 are so designed that when the presser foot bar is elevated and the label holder is swung into its upper or label receiving position, the parts 32 and 33 are lifted and the stops 30-30 therefore are moved into their operative positions, as shown in Fig. 11, where they determine the position of the forward edge of the label in the holder. When the presser foot is depressed and the holder is swung into its lower position, where it presents the label in position to be engaged by the needles, the parts 33 and 34 are moved downwardly and this movement is transmitted to the stops 30-30, tipping them into their raised or inoperative positions, as shown in Fig. 8.

When the label L is placed in the holder its ends are guided by the upturned sides of the plate 16. The plate 10, however, is not as wide as the plate 16, and the end portions 60 of the label, therefore, project beyond the opposite edges of this plate, as clearly shown, for instance, in Fig. 12. The forward movement of the label is limited at this time, as above stated, by the stops 30-30. 65 While the label is thus held in this position

on the plate 10, two folders 50 and 51, respectively, Figs. 12 to 14, engage the opposite ends of the label and turn them downwardly and inwardly under the plate 10.

These folders are formed integral with blocks 52 and 53, respectively, which are slidably mounted on the bar 34, each block being pinned through the bar and the pins entering slots in the bar and bearing against opposite ends of a coiled spring 54 which thus holds the blocks apart. In addition to carrying the folders 50 and 51, each block also has a depending finger, designated at 56 and 57, respectively, Fig. 12, and these fingers engage the opposite ends of the label 80 after it has been placed on the plate 10 and thus serve to position it longitudinally.

When the label is first placed in the holder the folders occupy substantially the relationship to the holder shown in Fig. 12. Immediately after the holder has begun to move back toward its label presenting position, the bar 34 is depressed through its connections with the cams 40 and 41, as above described, and this movement enables the folders to bend the ends of the label downwardly past the edges of the plate, as clearly shown in Fig. 13. The folders are next moved inwardly toward each other enabling them to fold the ends of the label under the plate 10, as shown in Fig. 14, and for the purpose of producing this movement an additional cam operated mechanism is provided. This mechanism comprises two cams 58 and 59 adjustably secured to the outer faces of the respective cam disks 40 and 41. A screw 60, Fig. 8, secures the cam 58 in place and passes through a slot in the disk 40 so that the angular relationship between the two parts 40 and 58 may be adjusted. The parts 41 and 59 are similarly secured together. These cams are adapted to act, respectively, on the upper ends of levers 62 and 63 fulcrumed on blocks 64 and 65, respectively, which are secured to the rods 36 and 37 previously referred to. The lower ends of these levers are turned inwardly, as clearly shown in the drawings, and bear against disks 66 and 67, respectively, which are fastened to the respective blocks 52 and 53. The screws that secure these disks in place are eccentrically positioned in the disks so that the movements of the two blocks relatively to the plate 10 may be adjusted. This mechanism is timed to cause the folders to turn the ends of the label under, as shown in Fig. 14, prior to the completion of the downward movement of the holder.

The downward and inward movement of the holder carries the forward edge of the label under the points of the needles 5-5 so that as soon as the machine is started into operation the needles will descend, entering the label near its opposite ends, and as the machine continues to operate, the

- usual feeding mechanism will draw the label out of the holder, the stops 30—30 at this time being raised. Mechanism is provided for automatically stopping the machine after the needles have made a predetermined number of stitches and for causing the needles to make superposed stitches at the beginning and end of the line of stitches or seam made by each needle.
- Referring to Figs. 1, 6 and 7, the fast and loose pulleys of the machine are shown at 70 and 71, respectively, and the driving belt at 72. The position of the belt is controlled by a shipper fork 73 mounted on a bracket 74 which is fulcrumed at 75 and is normally held with the belt on the loose pulley 71 by means of a spring 76 included in the connections between the bracket 74 and the treadle 77. When this treadle is depressed the bracket 74 is rocked in a counter-clockwise direction, Fig. 1, thus throwing the belt 72 on to the fast pulley 70 and starting the main shaft 78 of the machine. Another shaft 80 is driven through a bevel gear connection 81 with the shaft 78 and carries a worm 82 driving a worm wheel 83 fast on a horizontal shaft 84 which is mounted at the rear of the machine. This shaft carries a cam 85 which operates a brake lever 86, and it also carries a throw-out cam 87 adapted to actuate, at certain times, a dog 88 which is pivoted on a screw 113, Fig. 7. After the machine has been started into operation a spring 89, acting through the dog 88, holds the shipper fork 73 in its running position; but when the machine has made a predetermined number of revolutions, and therefore has produced a given number of stitches, one of the projections of the cam 87 engages the dog 88 and swings it away from the fork 73, thus allowing the spring 76 to shift the belt 72 automatically on to the loose pulley 71. At the same time that this happens, the cam 85 operates the lever 86 to apply the brake to the fast pulley 70 and thus slow up the machine. Also, while these operations are taking place a pin 90, Fig. 7, projecting from the pulley 70, is engaging a curved arm 91 which projects laterally from a head formed on the upper end of a post 92 which is mounted in the bracket 74 and is held in its raised position by a spring 93. The pin 90 thus depresses the arm 91 against the tension of the spring 92 and finally comes to rest in a socket 94 in the head thus stopping the machine in a predetermined position with the needles 5—5 elevated. It will be understood that when the treadle 77 is depressed again to start the machine, the connections with the bracket 74 tip it far enough to disengage the socket 94 from the pin 90 so that these parts then will not interfere with the starting of the machine.
- The feeding movement of the work is effected in the usual manner through connections with a feed lever 96, Fig. 1, but this feeding movement is, according to the present invention, controlled in a novel manner. The lever 96 forms essentially an eccentric strap running on a tubular projection or sleeve 97, Fig. 4, extending from a plate 98 secured to the face of a disk 99 mounted fast on the shaft 78. The plate 98 is pivoted on a screw 100, and its range of movement is limited by another screw 101 projecting through a slot formed in the opposite edge of the plate. A spring 102, mounted in one side of the plate 98, presses a block 103 against the surface of the shaft 78 and tends to swing the plate 98 about the pivot 100, this movement, however, being limited by an adjusting screw 103' which is mounted in the opposite side of the plate 98 and has an end projecting through a hole formed in the shaft 78 and bearing against the tip of a plunger 104 located axially in the shaft 78. This plunger has a reduced tip 105, Fig. 5, and a slightly larger portion 106 immediately behind the tip 105. When the adjusting screw 103' engages the tip 105, the plate 98 is then held by the spring 102 and pin 103 with the sleeve 97 in a concentric relationship to the shaft 78. Consequently, no oscillating movement will be imparted to the feed lever 96 at this time. When, however, the plunger is moved inwardly to bring the part 106 thereof in engagement with the screw 103', the plate 98 will be tipped to the right, Fig. 100 4, thus moving the sleeve 97 into an eccentric position. The sleeve now imparts an oscillating movement to the lever 96 which, in turn, operates the usual work feeding mechanism.
- The inward and outward movement of the plunger 104 is produced by a cam 108, Figs. 6 and 7, secured fast on the shaft 84. This cam has a cam path 109 to receive a roll 110, mounted on the end of a lever 112, which is fulcrumed on a screw 113 and carries another roll 114 at its opposite end running between the flanges of a grooved collar 115 secured on the end of the plunger 104. The cam path 109 is so designed that when the machine starts into operation the needles 5—5 make two stitches without feeding. Their normal feeding movement is then begun and continued until a predetermined number of stitches have been made through each end of the label. Then, as the machine is about to stop automatically, the needles make two more stitches without feeding. These superposed stitches at the opposite ends of each seam tie the thread sufficiently to prevent it from unravelling.
- It will now be understood that it is merely necessary for the operator to place a label in the holder 16, this operation being performed when the machine is stopped and the

presser foot raised, and then to depress the presser foot either by moving the presser foot lever 116, Fig. 8, or by depressing a treadle which is connected with the presser foot in a manner usual in machines of this type. This results in automatically turning under the ends of the label and presenting the label in proper position for engagement by the needles. The operator next depresses the treadle 77 and immediately releases it again, this operation serving to start the machine into action, whereupon it automatically causes the needles to sew across the opposite ends or edges of the label and stop automatically. The operator then removes the work, cuts the threads, replaces another piece of work, introduces another label, and repeats the operations just described.

The machine performs the label sewing operation very neatly and more rapidly than the machines heretofore used for this purpose.

While I have herein shown and described the best embodiment of the invention which I have so far devised, it will readily be appreciated that the invention is susceptible of embodiment in many forms differing in details of construction from the arrangement shown. I do not wish, therefore, to be limited to the particular construction shown. It will also be appreciated that while I have described the machine as adapted particularly for sewing on labels, since this is an important commercial field for the machine, it is, nevertheless, adapted to other uses where two parallel lines of stitches are to be made and the machine stopped automatically.

Having thus described my invention, what I desire to claim as new is:

1. In a sewing machine having two needles spaced apart, the combination of means for presenting a label in position to have its opposite edges sewed to the work simultaneously by said needles, mechanism for causing said needles to make overlapping stitches at the start and finish of the sewing operation, and means for automatically stopping the machine when said sewing operation has been completed.

2. In a sewing machine having two needles spaced apart and mechanism for operating said needles, the combination of means for presenting a label in position to have its opposite edges sewed to the work simultaneously by said needles, and mechanism for causing said needles to make overlapping stitches at the start and finish of the sewing operation.

3. In a sewing machine having two needles spaced apart and mechanism for operating said needles, the combination of means for presenting a label in position to have its opposite edges sewed to the work simultaneously by said needles, and auto-

matic mechanism for causing said needles to make a plurality of substantially superposed stitches at each end of the seam made by each needle.

4. In a sewing machine having two needles spaced apart and mechanism for operating said needles, the combination of means for presenting a label in position to have its opposite edges sewed to the work simultaneously by said needles, and automatic mechanism for modifying the action of the feeding mechanism of the machine to cause the needles to make overlapping stitches at the start and finish of the sewing operation.

5. In a sewing machine having two needles spaced apart and mechanism for operating said needles, the combination of means for presenting a label in position to have its opposite edges sewed to the work simultaneously by said needles, and mechanism for causing said needles to make a predetermined number of stitches and then stop automatically.

6. In a sewing machine having two needles spaced apart and mechanism for operating said needles, the combination of means for presenting a label in position to have its opposite edges sewed to the work simultaneously by said needles, manually operated means for controlling the starting of the machine into operation, and automatic means for stopping the machine when said needles have made a predetermined number of stitches.

7. In a sewing machine having two needles spaced apart and mechanism for operating said needles, the combination of means for presenting a label in position to have its opposite edges sewed to the work simultaneously by said needles, said label presenting means including a holder for the label, and means for gaging the position of the label in said holder.

8. In a sewing machine having two needles spaced apart and mechanism for operating said needles, the combination of means for presenting a label in position to have its opposite edges sewed to the work simultaneously by said needles, said label presenting means including a holder for the label, and stops for determining the position of the label in said holder.

9. In a sewing machine having two needles spaced apart and mechanism for operating said needles, the combination of means for presenting a label in position to have its opposite edges sewed to the work simultaneously by said needles, said label presenting means including a holder for the label, stops for determining the position of the label in said holder, and mechanism for moving said stops into and out of their operative positions.

10. In a sewing machine having two needles spaced apart and mechanism for op-

- erating said needles, the combination of a holder for presenting a label in position to enable said needles to sew the opposite ends of said label simultaneously to the work, 5
 5 and means for moving said holder into and out of position to present a label properly for said sewing operation.
11. In a sewing machine having two needles spaced apart, mechanism for operating said needles and a presser foot mechanism, the combination of a holder for presenting a label in position to have its opposite edges sewed to the work simultaneously by said needles, and means connected with 10
 15 said presser foot mechanism and arranged to be operated thereby for moving said holder from a label receiving position into position to present a label to said needles for the sewing operation.
12. In a sewing machine having two needles spaced apart and mechanism for operating said needles, the combination of means for presenting a label in position to enable said needles to sew the opposite ends 20
 25 of said labels simultaneously to the work, said means comprising a holder including a plate on which a label rests with its ends projecting beyond the edges of the plate, and devices for engaging said projecting ends 30 and folding them under the plate.
13. In a sewing machine having two needles spaced apart and mechanism for operating said needles, the combination of means for presenting a label in position to enable said needles to sew the opposite ends 35
 40 of said labels simultaneously to the work, said means comprising a holder including a plate on which a label rests with its ends projecting beyond the edges of the plate, folders for engaging said projecting ends, and mechanism for relatively moving said plate and folders to cause the folders to turn the ends of the label downwardly and inwardly under the plate.
14. In a sewing machine having two needles spaced apart and a presser foot 45
 50 mechanism, the combination of means for presenting a label in position to enable said needles to sew the opposite ends of said labels simultaneously to the work, said means comprising a holder including a plate on which a label rests with its ends projecting beyond the edges of the plate, folders for engaging said projecting ends, and mechanism connected with the presser foot 55
 60 mechanism of the machine and arranged to be operated thereby for relatively moving said plate and folders to cause the folders to turn the ends of the label downwardly and inwardly.
15. In a sewing machine having two needles spaced apart and a presser foot mechanism, the combination of means for presenting a label in position to enable said needles to sew the opposite ends of said 65
 70 labels simultaneously to the work, said means comprising a holder including a plate on which a label rests with its ends projecting beyond the edges of the plate, folders for engaging said projecting ends, mechanism connected with the presser foot mechanism of the machine and arranged to be operated thereby for relatively moving said plate and folders to cause the folders to turn the ends of the label downwardly 75
 80 and inwardly, and means arranged to be operated by said presser foot mechanism to move said holder into position to present the edge of the folded label under said needles.
16. In a sewing machine having two needles spaced apart and a presser foot mechanism, the combination of a holder for presenting a label in position to have its opposite edges sewed to the work simultaneously by said needles, and means connected with said presser foot mechanism and arranged to be operated thereby for moving said holder from its label receiving position into label sewing position and for returning the holder again to its label receiving position. 85
